UNITED STATES PATENT OFFICE

2,037,152

LIQUID AGITATOR

Mark S. Scofield, Columbus, Ohio, assignor to
Ralph S. Scofield, Newton, Iowa

Application March 5, 1934, Serial No. 714,129

2 Claims. (Cl. 68—37)

My invention relates to liquid agitators of the type in which liquid is agitated by the application of air thereto, especially where it is desirable to create "suds".

5 More particularly, it is my object to provide a liquid agitator structure, including means for supplying air to liquid in a container and for re-using the same air and for creating a slight suction of air into the container, particularly 10 around a lid or cover at the top of the device.

The purpose of such a structure is to provide for efficient agitation and the satisfactory creation of soap suds and to prevent the water or suds from emerging from the container and collecting on the top thereof.

15 My agitator may be used for washing machines, dish washers and other apparatus where the creation of soap suds is desirable.

For purposes of illustration, I have shown my 20 agitator embodied in the form of a washing machine.

With these and other objects in view, my invention consists in the construction, arrangement and combination of the various parts of 25 my liquid agitator, whereby the objects contemplated are attained, as hereinafter more fully set forth, pointed out in my claims, and illustrated in the accompanying drawing, in which:

Figure 1 is a front elevation of a washing machine embodying an agitator involving my invention, parts being broken away and parts being shown in section.

Figure 2 is a horizontal, sectional view taken 30 on the line 2—2 of Figure 1.

Figure 3 is a vertical, detailed, sectional view taken on the line 3—3 of Figure 2.

Figure 4 is a detailed, sectional view taken 35 on the line 4—4 of Figure 3; and

Figure 5 is a detailed, sectional view taken on the line 5—5 of Figure 2.

40 In the drawing herewith, I have shown a washing machine having an outer shell 10 in the form of a metal cylinder supported on legs 11 provided with rollers 12.

45 Resting on the top of the shell 10 is an apron 13 in the form of an annular, substantially flat ring inclined inwardly and slightly downwardly from the wall of the shell 10 and substantially overhanging the top of the tub 14.

50 The tub 14 is supported in any suitable way within and spaced from the wall of the shell 10. As here illustrated, the under side of the apron 13 is provided with an annular flange 15 fitting the inside of the wall of the shell 10 and with an 55 inwardly spaced downwardly projecting annular

flange 16 arranged to project downwardly just inside the wall of the tub 14.

The tub 14 has at its upper edge the outwardly extending flange 17. I arrange a gasket 18 in the form of a rubber hose between the flange 17 and the under face of the apron 13.

A series of lugs 19 project downwardly from the apron and locking plates 20 are fastened to the lugs 19 as by screw bolts 21 and are so arranged as to engage under the flange 17 for holding the tub in place.

In the form of the device shown here, I have illustrated a cover 22 hinged at 23 to the apron 13 for closing the central opening in the apron and thus closing the tub. The cover, of course, 15 may vary in structure but the cover 22 will suffice for illustrating my invention.

It will be understood that the tub may be provided with suitable drain means, which however forms no part of my present invention and is therefore not shown in the drawing. The mechanism may also be provided with a wringer and means for operating it, and I have shown the wringer post P, but since the wringer mechanism forms no part of the present invention, 25 I have not further illustrated it.

Suitably supported below the tub is an air pump or blower 24 operated from any source of power, for instance the motor 25. The pump 30 discharges air into a pipe 26, which extends upwardly alongside the tub and within the shell 10 and to a point near the top of the tub, and from whence it is inclined downwardly again to a point below the bottom of the tub to thus afford 35 a proper water seal.

The air is supplied from the pipe 26 to the lower interior of the tub 14 through a distributor 27, which may be similar in its general structure to that disclosed in my patent, No. 1,797,- 40 622, issued March 24, 1931, and particularly in Figure 3 thereof.

The air for the blower is drawn from the interior of the tub.

I have shown an air and moisture separator 45 28 in the form of a casing secured to the side of the tub, which is larger at its upper end than at its lower end, and is connected with the blower intake by a pipe 29.

The casing of the separator 28 is closed except 50 as herein mentioned.

At the upper part of the separator 28 its interior communicates with the tub by means of a passage 30 through the wall of the separator 28 and the wall of the tub. Registering with the 55

passage 30, a cup-like member 31 is arranged on the inside of the tub.

It will be understood that the air is drawn from the interior of the tub through the cup-like member 31 and the passage 30 and it follows the paths indicated by the arrows in Figures 3 and 4.

On the interior of the separator 28 the casing is provided with a pair of laterally spaced partitions 32 extending from the top of the casing 10 downwardly below the passage 30 and extending into the upper end of a compartment 33 formed in the casing by means of a partition 34. This compartment 33 is open at its upper end as shown and is otherwise closed, except for the tube 35, 15 which leads from its lower part into the tub. There will, of course, be some moisture carried into the separator with the air.

The air follows a tortuous path as indicated by the arrows in Figure 4 and the moisture tends to 20 drop into the compartment 33 where it stands substantially on the level with the water in the tub.

It will thus be seen that in the operation of the device, the air is drawn from the tub through 25 the blower and discharged into the bottom of the tub and passes upwardly through the water, thus serving to agitate it.

It will be understood that by adding soap a desired suds may be produced.

30 I have found that by using air for the agitator instead of employing a mechanical agitator, I am able to create and maintain a much better supply of suds.

The soap bubbles gather at the top of the 35 water in the tub in such quantity that they tend to get out through the joint around the lid and pile up on top of the tub. This is a decided objection to washing machines and the like which employ air for agitating water and washing the 40 clothes and forming a suds. Much complaint has been experienced because of the fact that the suds gather in a pile on top of the tub.

I have provided means for creating slight vacuum in the tub and thus for creating a slight suction around the cover, and thus preventing the collection of soap bubbles on top of the tub.

Extending from the upper part of the pipe 26 is a short tube 36 to the lower part of a horizontal cylindrical casing 37 of what may be called a 50 vacuum generator and moisture separator. A short pipe 38 leads from the lower part of the opposite end of the casing 37 to a passage 39 in the wall of the casing 28 discharging into the interior of the casing at 40 (Figure 2) above the 55 compartment 33.

In the casing 37 is a vertical partition 41 spaced from the tube 36 but nearer that tube than the tube 38. The partition 41 has a series of small holes 42 in its upper part. Spaced from the partition 41 and between it and the tube 38 is another partition 43 extending from the upper part of the casing 37 substantially more than half way to the bottom thereof, and thus leaving an opening around its lower edge.

60 Preferably in the top of the casing 37 between the partition 43 and the outlet end of the casing is an air vent 44 to open atmosphere.

The casing 37 may be filled with gravel, charcoal or the like.

In the use of the vacuum generator, it will be seen that when air is forced by the blower through the pipe 26, some of the air will pass 5 through the small tube 36 into the casing 37, and will, of course, be substantially retarded by the charcoal or the like, indicated at 45, which may fill or partly fill one or more of the compartments formed by the partitions, and the air will follow 10 a tortuous path through the openings 42 and around the lower edge of the partition 43 and thence through the vent 44.

The moisture and soap carried by the air will tend to collect on the charcoal 45 or the like and 15 will then flow out through the tube 38 into the air and moisture separator and drop into the compartment 33.

Thus a small part of the air pulled from the tub by the blower will be discharged to atmosphere through the vent 44. This will create a slight vacuum in the top of the tub and will tend to cause slight inflow of air into the tub around the cover 22. This inflowing air will prevent the escape of soap bubbles around the cover and prevent the collection of a pile of soap bubbles on top of the tub.

By this arrangement, I am able to utilize the advantages of air agitation of the water in a washing machine or the like, and am able to 30 take advantage of the creation of a large amount of suds and at the same time to prevent the escape of the suds from the tub and the collection thereof on the top of the tub and on the apron 13.

It will, of course, be understood that some 35 changes may be made in the construction and arrangement of the parts of my improved structure, and it is my purpose to cover by my claims any modified forms of structure or use of mechanical equivalents, which may be reasonably included 40 within their scope.

I claim as my invention:

1. In a washing machine, a tub, a cover therefor, around which suds might escape and means for supplying air to the water in the tub for agitating it without allowing suds to escape around the cover, said means including a compressor air pump, a distributor chamber for distributing air into the lower part of the tub, pipe means leading from the pump discharge outlet upwardly to 45 a point above the water level in the tub and thence downwardly into the distributor chamber, said pipe means being provided with a small vent to atmosphere, and means for conducting air from the upper interior of the tub to the pump 50 inlet.

2. In a device of the kind described, a washing machine tub, a cover therefor, around which suds might escape and around which air may be drawn 55 into the tub, an air pump, air conducting means leading from the pump to the lower interior of the tub, air conducting means leading from the upper interior of the tub to the pump and a communicating passage leading from said first means to said second means, having a small vent 60 to atmosphere.

MARK S. SCOFIELD.
